UNITED STATES PATENT OFFICE.

JOSEPH RESHOWER AND AUGUST HECK, OF NEW YORK, N. Y.

DESIGN FOR A BANNER-ROD.

SPECIFICATION forming part of Design No. 17,877, dated November 8, 1887.

Application filed June 21, 1887. Serial No. 242,052. Term of patent 7 years.

To all whom it may concern:

Be it known that we, JOSEPH RESHOWER and AUGUST HECK, of New York, in the county and State of New York, have invented 5 a new and original Design for Banner-Rods, &c., of which the following is a specification.

This design consists, essentially, in a banner-rod or like article having the ends enlarged and shaped like a lawn-tennis racket. 10 It also has a number of transverse lines on the rod proper.

The accompanying drawing represents a banner-rod embodying our design, and shows part of a banner connected therewith.

15 A designates the rod proper. B designates its enlarged ends. It will be seen that they are made in the shape of lawn tennis rackets, the continuous central portion of the rod representing the united handles of the same. The 20 rod has a number of transverse lines appear-

ing thereon. Cords C, or portions of a cord, extend divergently to the ends of the rod, so as to form a triangle therewith. Cords D, or portions of a cord, extend from the ends of the rod divergently to rings E or a banner, F, 25 their ends being tied in a bow, which hangs over the banner.

What we claim as our invention, and desire to secure by Letters Patent, is—

A banner or like article having enlarged 30 ends in the shape of a lawn-tennis racket, the continuous portions of the rod representing the united handles of the same and having the appearance of transverse lines, substantially as described and shown.

JOSEPH RESHOWER.
AUG. HECK.
